UNITED STATES PATENT OFFICE.

DAVID H. FLOYD, OF ATLANTA, GEORGIA.

PLOW.

1,105,264.

Specification of Letters Patent.

Patented July 28, 1914.

Application filed July 12, 1913. Serial No. 778,659.

To all whom it may concern:

Be it known that I, DAVID HARVARD FLOYD, a citizen of the United States, and resident of Atlanta, in the county of Fulton and State of Georgia, have invented certain new and useful Improvements in Plows, of which the following is a specification.

This invention relates to certain improvements in plows and more particularly to 10 means for adjusting the plow share in respect to the beam.

In my improved construction I pivotally connect the plow share to the beam and my invention involves the means for locking the 15 share in position after having properly adjusted it about its pivotal connection. This locking means is preferably so constructed that it may be operated without the use of any tools and thus the plowman while in the 20 field may readily change the adjustment at any time desired. The locking mechanism is also so constructed that the adjustment can not be effected until a complete release of the locking member and thus a slight 25 loosening of the locking member does not permit any relative movement of the beam and share or any lost motion.

Reference is to be had to the accompanying drawings in which similar characters 30 of reference indicate corresponding parts throughout the several views, and in which—

Figure 1 is a perspective view of a plow constructed in accordance with my invention; Fig. 2 is a side elevation of a portion 35 of the beam and the plow share showing the latter in two adjusted positions; Fig. 3 is a top plan view of the parts shown in Fig. 2; Fig. 4 is a perspective view of one member of the locking mechanism; and Fig. 40 5 is a perspective view of the second member of the locking mechanism.

In the specific form illustrated, the foot 10 of the standard has two branches or arms 11-11 extending upwardly and thence forwardly and disposed upon opposite sides of the beam 12. A bolt 13 or any other suitable means serves as a pivotal connection between the foot or standard and the beam and permits the lower portion or point of 45 50 the standard to swing forwardly and upwardly in a vertical plane.

I have illustrated a very simple form of plow standard but I wish it distinctly understood that my invention does not relate 55 to the construction of the lower portion of

the standard and that any other suitable form might be employed.

My invention, involves particularly the means for securing the upper front ends of the arms 11-11 to the plow beam, so as to 60 hold the standard and beam rigid in respect to each other.

As shown the front ends of the arms are connected by a transverse pin 14 and on the upper surface of the beam is mounted a slide 65 15, shown particularly in Fig. 4. The slide is mounted for movement through a limited distance longitudinally of the beam and is held against removal from the latter. The lost motion attaching means preferably includes two pins 16 and 17 extending through slots 18 and 19 in the slide. The length of said slots determines the amount of end-wise movement of the slide, and the heads of the pins 16 and 17 prevent the removal of the 70 slide. The slide is provided with one or more upwardly extending brackets 20 provided with recesses or notches 21 adapted to receive the cross pin 14 of the plow standard. The said notches or recesses preferably 75 enter from an edge curved in an arc having the bolt 13 as the center so that they are all at equal distances from the pivotal connection, and their opposite sides are parallel 80 and spaced a distance equal to the diameter 85 of the pin. The range of movement and the position of the slide are such that when it is moved end-wise in one direction the pin 14 may enter any one of the recesses and thus 90 lock the standard against movement about 95 its pivot. With the slide in the opposite limiting position the pin is free from the bracket and the standard may be freely 100 swung.

For positively retaining the slide in locking position I may employ the locking member shown particularly in Fig. 5. This is an eccentric head 22 for the rear pin 17 and disposed between stops 23 on the upper surface of the slide and adjacent opposed ends 105 of the slot 19. With the eccentric in the position shown in Fig. 3 it engages with both the stops and positively prevents the rearward movement of the slide or the disengagement of the pin 14. When it is desired to adjust the plow standard the eccentric may be turned about the pin 17 as a center by means of a flange or ridge of the upper surface of the eccentric. By turning the eccentric one-half of a revolution or 110

possibly less, the slide is automatically moved rearwardly to such an extent as to free the pin 14 and permit the free swinging of the plow standard. It will be noted that it is only necessary to turn the eccentric to lock or unlock the plow share and that no tools of any kind are required to operate the parts. I have shown two separate brackets 20 adjacent the two arms 10 11—11, but it is evident that only one need be employed if it be made of sufficient width and strength and a larger or smaller number of recesses 21 could be employed dependent upon the desired range of adjustment.

Various changes may be made within the details of construction, within the scope of the appended claims and without departing from the spirit of my invention.

20 The plow is provided with handles 25 which are preferably adjustable both angularly and longitudinally in respect to the beam, but this adjusting means forms no portion of my present invention. As shown 25 a non-rotatable circular plate 26 is secured to each of the two opposite sides of the beam and is provided with an annular row of teeth or serrations which engage with a corresponding row in a second plate 27. This 30 latter plate is provided with a groove 28 in its outer surface, deeper at one end than at the other so as to receive the handles and permit the desired spreading apart of the latter toward the outer ends. A clamping 35 bolt 29 passes through both pairs of plates and through the handles, and has washers 30 between the outer surfaces of the handles and the head and nut of the bolt. The handles are provided with longitudinal slots 40 31 which permit of an end-wise adjustment of the handles. The outer plate 27 may have a stud projection 32 disposed within said slot, to prevent said portions from being bent toward each other or otherwise injured.

45 Having thus described my invention, what I claim as new and desire to protect by Letters-Patent is:

1. A plow having a beam, a standard pivoted thereto and having a forwardly extending arm, a slide carried by said beam and having a series of recesses therein, a projection on said arm adapted to enter any one of said recesses and hold said arm in adjusted position in respect to said beam, and 50 means for locking said slide against relative movement in respect to said beam.

2. A plow having a beam, a slide upon the upper surface thereof and having an upwardly extending bracket provided with recesses in the front edge thereof, a plow 60 standard secured to said beam and relatively movable in respect thereto, said standard having a portion projecting adjacent said bracket and adapted to enter into any one of said recesses to lock said share in adjust- 65 ed position relative to said beam.

3. A plow having a beam, provided with a slide upon the upper surface thereof, said slide having an upwardly extending bracket provided with recesses in the front edge 70 thereof, a plow standard secured to said beam and relatively movable in respect thereto, said standard having a portion projecting adjacent said bracket, and adapted to enter into any one of said recesses to lock 75 said standard in adjusted position relative to said beam, and means for locking said slide against movement.

4. A plow having a beam, a slide upon the upper surface thereof, and having an upwardly extending bracket provided with recesses in the front edge thereof, a plow standard secured to said beam and relatively movable in respect thereto, said standard having a portion projecting adjacent said 80 bracket and adapted to enter into any one of said recesses upon the proper relative movement of said standard and slide to lock said standard in adjusted position relative to said beam, and an eccentric in engagement with said slide for moving the latter and locking the same against movement.

5. A plow having a beam, provided with a slide upon the upper surface thereof, said slide having an upwardly extending bracket 95 provided with recesses in the front edge thereof, a plow standard pivotally secured to said beam and having a portion projecting forwardly along said standard and terminating adjacent said bracket and having 100 a projection adapted to enter into any one of said recesses to lock said standard in adjusted position relative to said beam, and means for locking said slide against movement.

Signed at Atlanta in the county of Fulton and State of Georgia this seventh day of July A. D. 1913.

DAVID H. FLOYD.
